US00D839239S

(12) **United States Design Patent** (10) Patent No.: **US D839,239 S**
(45) Date of Patent: ** *Jan. 29, 2019

(54) **AUDIO VISUAL BOX FOR TV RECEIVER**

- (71) Applicant: **LG ELECTRONICS INC.**, Seoul (KR)
- (72) Inventors: **Yooseok Kim**, Seoul (KR); **Sunha Park**, Seoul (KR); **Younsoo Kim**, Seoul (KR); **Byungmu Huh**, Seoul (KR)
- (73) Assignee: **LG ELECTRONICS INC.**, Seoul (KR)

(*) Notice: This patent is subject to a terminal disclaimer.

(**) Term: **15 Years**

(21) Appl. No.: **35/503,388**

(22) Filed: **Jan. 20, 2017**

(80) **Hague Agreement Data**

Int. Filing Date: **Jan. 20, 2017**

Int. Reg. No.: **DM/094543**

Int. Reg. Date: **Jan. 20, 2017**

Int. Reg. Pub. Date: **Jul. 21, 2017**

(30) **Foreign Application Priority Data**

Jul. 28, 2016 (KR) 30-2016-0037088

(51) **LOC (11) Cl.** **14-01**
